UNITED STATES PATENT OFFICE.

THOMAS GORMAN, OF WARREN, RHODE ISLAND, ASSIGNOR OF ONE-HALF
TO FRANK HAIL BROWN, OF WARWICK, RHODE ISLAND.

DESIGN FOR A BOLSTER.

SPECIFICATION forming part of Design No. 28,104, dated December 28, 1897.

Application filed March 19, 1896. Serial No. 583,976. Term of patent 14 years.

To all whom it may concern:

Be it known that I, THOMAS GORMAN, of Warren, county of Bristol, State of Rhode Island, have invented and produced a new and original Design for a Spinning-Machine Bolster, of which the following is a specification, reference being had to the accompanying drawing.

The design is illustrated in the accompanying drawing, in which the figure is a perspective view of a bolster embodying the present design.

The leading feature of the design resides in a bolster having two projecting lugs.

In the drawing, A represents the bolster, 15 provided with the bore A' and also provided with two lugs or projections A², which lugs give to the bolster a peculiarly characteristic appearance.

What I claim is—

20 The design for a bolster substantially as shown and described.

THOMAS GORMAN.
